(57) **CLAIM**

The ornamental design for a valve plate for gate valve, as shown and described.

DESCRIPTION

FIG. 1 is a front, top and left side perspective view of a valve plate for gate valve showing my new design;

FIG. 2 is a rear, bottom right left side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof;

FIG. 8 is a right side view thereof; and,

FIG. 9 is a sectional view taken along line 9-9 of FIG. 5. The broken lines depict portions of the valve plate for gate valve that form no part of the claimed design.
